US0D1061621S

(12) **United States Design Patent** (10) Patent No.: **US D1,061,621 S**
(45) Date of Patent: ** Feb. 11, 2025

(54) **EXHAUST MANIFOLD**

(71) Applicant: **BD ENGINE BRAKE**, Abbotsford (CA)

(72) Inventor: **Ryan Richman**, Surrey (CA)

(73) Assignee: **BD ENGINE BRAKE**, Abbotsford (CA)

(**) Term: **15 Years**

(21) Appl. No.: **29/867,596**

(22) Filed: **Oct. 31, 2022**

(51) LOC (15) Cl. **15-01**

(52) U.S. Cl.

USPC **D15/5**; D12/194

(58) Field of Classification Search

(57) **CLAIM**

The ornamental design for an exhaust manifold as shown and described.

DESCRIPTION

FIG. 1 is a bottom perspective view showing my new design for an exhaust manifold;

FIG. 2 is a top perspective view thereof;

FIG. 3 is a bottom view thereof;

FIG. 4 is a front view thereof;

FIG. 5 is a back view thereof;

FIG. 6 is left view thereof;

FIG. 7 is a right view thereof; and,

FIG. 8 is a top view thereof.

The broken lines are shown for the purpose of illustrating parts of the article. None of the broken lines form part of the claimed design.

1 Claim, 8 Drawing Sheets
